UNITED STATES PATENT OFFICE.

GILBERT C. BEMIS, OF LACONIA, NEW HAMPSHIRE.

TOP-SUPPORTER FOR BOOTS OR SHOES.

SPECIFICATION forming part of Letters Patent No. 635,034, dated October 17, 1899.

Application filed January 30, 1899. Serial No. 703,802. (No model.)

To all whom it may concern:

Be it known that I, GILBERT C. BEMIS, a citizen of the United States, residing at Laconia, in the county of Belknap and State of New Hampshire, have invented a new and useful Top-Supporter for Boots or Shoes, of which the following, together with the accompanying drawings, is a specification sufficiently full, clear, and exact to enable persons skilled in the art to which this invention appertains to make and use the same.

The object of my present invention is to provide means for maintaining boot or shoe uppers in proper shape and prevent breaking down or crinkling at the ankle-top or leg portion thereof during the process of manufacturing or in subsequent handling or exhibition of the shoe.

Another object is to provide for use, in connection with a last or relast mechanism, an appliance for supporting and keeping the top or leg portion of the boot or shoe upper spread and in relatively extended position, said appliance adapted for or capable of use as a standard or jacking attachment for sustaining the last in some of the operations of shoe manufacture.

I attain these objects by mechanism the nature and operation of which are illustrated in the drawings, wherein—

Figure 1 represents a side view of my improved supporter as applied to use in a shoe, the shoe and last being shown partly in section. Fig. 2 represents a top plan view of the same. Fig. 3 shows a modification in construction, and Fig. 4 is a front view of an attaching device for holding in eyelet-holes.

In accordance with my invention, which comprises a means for effective support, as shown in Fig. 1, I provide, in combination with a last A or relast appliance, a substantially upright stem or standard-rod B, which carries an upward outwardly-springing pair of arms C C' or lift devices furnished with gripping-jaws or suitable means at D D' for attachment to the top of the ankle or leg portion E' of the shoe-upper, preferably at the central front f and back b, and adapted for exerting thereon a thrust or yielding strain in upward and outward directions and with

sufficient force to keep the ankle or leg portion extended.

The standard or stem B is preferably made tubular, although in some instances it can be a solid rod, if desired. The lower end a is fitted into a hole in the last A, the top part projecting upward therefrom at laterally central position. The standard B can be set into the ordinary jack-spindle hole or a separate special hole can be formed therefor in the last. A collar or slide G is arranged on the standard, and the arms C C' are flexibly or pivotally attached thereto at 5, said arms projecting upward and outward to greater or less degree toward the front and rear. An expanding coil-spring H is arranged beneath the collar or slide for forcing the arms upward with a yielding pressure, the tension of said spring being made such as will give the required degree of force for any particular class of work. The arms can be curved or straight and carry at their upper ends the gripping-jaws D, connecting-hooks D', or other suitable means for attachment to the top of the shoe. The gripping or attaching means at D D' can be of any efficient and convenient construction whereby a proper hold of the arm upon the shoe may be readily secured and released. The device D for holding the back part of the upper is best made as a gripping-clamp, while that for the front part, at D', can be made either as a clamp or as a hook (see Fig. 4) to enter the top eyelet-holes e, or, again, as with loops to engage with lacing-studs, accordingly as the shoes on which the device is intended to be used are buttoned, laced, or studded at their front.

The length of the stem B and arms C C' and the throw of the spring H can be made more or less than herein shown, when desired, accordingly as the instrument is intended for use in boots or shoes having very high leg or moderately-high ankle portion. The spring H in itself affords an extent of adjustment that will accommodate the variations of size found in cases of similar-styled shoes.

The tube caliber or opening m in the outer end of the standard D is preferably made of such a dimension as will receive and fit upon an ordinary jack-spindle, so that the same

will serve for the holding or jacking of the work at various stages of the shoe manufacture, thus avoiding the necessity of crushing the leg portion of the upper down upon the 5 jacking mechanism.

When designed for employment in connection with a pneumatically-inflated last or re-last appliance—such, for instance, as that described in my other application of even date 10 herewith—the stem B can be made to serve as the air-induction tube for the inflation of the last-body and is then provided with a check-valve therein. Such construction is indicated by dotted lines at n on Fig. 1.

15 Fig. 3 shows a modification in construction, wherein the arms are joined by a cross-bar G², that passes through a longitudinal slot S, formed in the standard B, while the spring H⁴ is arranged within the standard, or, if 20 preferred, such spring may be on the exterior thereof and the standard can be made solid or non-tubular. In this modification the two arms can both be formed of a single piece of wire or metal, the arms having a certain degree 25 of resilience to give greater or less spread at the top.

In the operation, the stem B being in position in the last A and the last within the shoe E, the spring H is pressed down sufficiently to permit the clamps D or hooks D' to be attached. Said clamps and hooks are then secured to the top part of the leg or ankle portion at its front f and back b, as indicated, and the spring H is then released. The 35 action of the spring and the outward swing of the arms exerts a strain upon the upper upwardly and outwardly in the directions indicated by arrows, Fig. 1, thus holding the top or ankle portion E' extended and spread 40 with its sides practically smooth and closely against the sides of the supporter. (See Fig. 2.) The supporter is inclosed almost entirely within the shoe, so that it does not interfere with the handling of the shoe in the works. 45 The stem maintains upright relation, while the spring and outward swing of the arms acting within the shoe to impart a yielding but sufficient force to keep the ankle or leg portion extended and prevent it from folding 50 or dropping over to one side at the top of the last or becoming wrinkled as the shoes are handled or stacked up in piles during the operation of their manufacture. The supporter can be readily removed by relieving 55 the strain and releasing the attachments at D and D'.

By dotted lines at L on Fig. 1 I have indicated a way in which the supporter and its elevating-spring can be made in a single piece

and applied to a last or relast appliance for 60 the support of the top of the shoe-upper.

I claim as my invention—

1. A supporter for the purpose specified, comprising a pair of upwardly and outwardly directed arms provided at their ends with 65 means for attachment to the top portion of the shoe-upper, said arms mounted upon a rod or centrally-disposed stem, the end of which is adapted for insertion within a hole formed in a last, for sustaining said supporter in 70 standing position within the shoe.

2. The combination with a last, of a top-supporter secured in or upon the last to occupy a standing position within the shoe, and having means for holding the top edge of the 75 upper, said supporter maintaining the leg or ankle portion of the upper extended by upward or outward thrust of said supporter, substantially as set forth.

3. A shoe-top supporter comprising a standard adapted for insertion in a last, and provided with an upwardly-directed spring-pressed arm or yielding member having, at the extremity thereof, means for attachment to and detachment from the top of the ankle 85 or leg portion of a shoe-upper, and adapted for giving a yielding or resilient action, for the purpose set forth.

4. A supporter comprising a standard or stem, a slide member movable longitudinally 90 in connection therewith, a pair of arms flexibly connected to said slide, gripping or attaching devices on said arms, and a spring upwardly acting against said slide, for the purpose set forth.

5. The combination, with a last, of an upright standard, its end supported in said last, upwardly furcated or projecting arms in movable connection with said standard, means at the ends of said arms for securing the same 100 to the top of the upper, and means for elevating the arms.

6. The combination, with a last, of a tubular standard having an end adapted for entering a hole in said last, and at its other end 105 a tubular portion with an opening adapted for the reception of a jack-spindle, the upwardly and outwardly extended arms movably connected with said standard, attaching devices on said arms for connection and disconnection thereof with a shoe-upper, and a spring normally elevating said arms.

Witness my hand this 20th day of January, 1899.

GILBERT C. BEMIS.
